Mr. Warner, Brown & Warner

UNITED STATES PATENT OFFICE

2,507,941

CLOSURE LOCK

Ralph C. Staley, Los Angeles, Calif.

Application November 27, 1945, Serial No. 631,002

2 Claims. (Cl. 292—19)

1

My invention relates to closure locks and more particularly to closure locks adapted to be used in connection with gas caps.

The object of my invention is to provide a closure lock for gas caps which will normally hold the cap in locked position to prevent accidental or unauthorized removal of the cap.

Another object of my invention is to provide a closure lock the locking means of which are normally arranged in locking position and will be put into inactive or open position by closing an electric circuit, which is normally open.

Other objects of my invention may appear in the following specification describing my invention and the accompanying drawing illustrating a preferred embodiment thereof. It is however to be understood, that my invention is not to be limited or restricted to the exact construction and combination of parts described in the specification and shown in the drawing, but that such changes and modifications can be made, which fall within the scope of the claims appended hereto.

In the drawing:

Figure 1 is a horizontal sectional view of my invention, some parts being shown in plan view, and

Figure 2 is a vertical sectional view, some parts being shown in elevation.

Referring to the drawing 10 represents the neck of a container (not shown) for gas or the like. Adjacent its upper end this neck has two laterally extending bulbs 11 from each of which a wall 12 projects forwardly, where they meet to form a forwardly extending half boss 13. The top surface of this half boss is level and has formed therein adjacent its forward end a semi-cylindrical hollow 14. In the rear portion of the top surface of the half boss 13 a semi-cylindrical depression 15 is formed extending coaxially with the hollow 14, and of the same diameter therewith. A stop 16 is arranged between the hollow 14 and the depression 15 forming a narrow communication 17 between them.

The bottom surface 18 of the half boss 13 extends rearwardly to the container neck 10. From the inner wall of said neck a bottom wall 19 extends forwardly the lower surface whereof may be looked upon as a continuation of bottom surface 18 of the half boss 13. The top surface of said bottom wall 19 is even and located at a somewhat lower level than the lowest part of the semi-circular depression 15. In the bottom wall of the half boss 13 a circular hole 20 extends from the semi-circular depression 15 downwardly

2

and is located approximately at the transverse center thereof.

A second half boss 21 is formed exactly like the above described half-boss 13. It has a semi-cylindrical hollow 22 corresponding with the hollow 14, a semi-cylindrical depression 23 corresponding with the depression 15 and a narrow communication 24 corresponding with communication 17. Walls of the same thickness and shape 10 as the walls 12 extend rearwardly from the second half boss 21, which forms the top half of a boss formed by the two half bosses.

The rear parts of the top walls end in bulbs similar to the bulbs 11 and these bulbs are connected with each other by means of a rear wall 25. This rear wall 25, the top bulbs, the top half boss and the walls between said half boss and said top bulbs are adapted to fit on top of the corresponding lower parts. The top parts, forming 20 one unit, are removably attached to said lower parts by flat head countersunk screws 26.

Into the top of the container neck 10, formed as described above, a stopper or cap 27 fits closely. This stopper has a top part 28 of a somewhat 25 bigger diameter than the inside diameter of the container neck 10. The stopper is provided with a circumferential groove 29. Two resilient arms 30 are embedded in the bulbs 11, one at each side of the neck 10, and extend forwardly. Their 30 forward ends are curved inwardly toward each other as shown at 31. These ends reach into the rear portion of the circular passage formed by the corresponding semi-circular depressions 15 and 23 through slots 32 provided in the wall of said 35 passage.

A plunger head 33 is slidably arranged in the circular passage. It has a stem 34 extending forwardly thereof and passing through the narrow communications 17 and 24 into the cylindrical hollow 14. On the front end of the stem 34 a circular disc 35 is rigidly mounted and a spiral spring 36 is arranged between the stop 16 and said disc, and surrounds the stem 34. The spring urges the disc 35 forwardly so that the forward surface 45 of the plunger head 33 abuts the stop 16. The rearward end of the plunger head 33 is frustoconically shaped and its rearmost part is located between the ends 31 of the resilient arms 30. The arms and the groove 29 are arranged at the same level so that said arms will normally engage said groove, thus preventing the removal of 50 the stopper 27.

On the bottom wall 19 rearwardly of the circular passage an electro-magnet 37 is arranged 55 coaxially with the plunger head 33. The magnet

is connected to a source of electricity 38 by means of wires 39 and 39' and in one of these wires a switch 40 is inserted.

The plunger head 33 has a slot 41 formed therein which extends diametrically therethrough. A pin 42 extends through said slot and is fastened in the hole 20 in the lower half boss 13 and a corresponding hole in the upper half boss 21.

When it is desired to remove the stopper 27 the switch 40 is closed energizing the magnet 37, which attracts the plunger head 33 moving it rearwardly against the pressure of spring 36. The frusto-conical portion of the plunger head will then engage the arm ends 31 and force said arms apart disengaging them from the groove 29, thereby permitting the removal of the stopper 27. The switch can then be opened again, de-energizing the magnet 37 and allowing spring 36 to move the plunger forwardly and out of engagement with the arm ends 31. The arms will then return into their original position on account of their inherent resiliency and will be ready to engage the groove 29 again; when the stopper 27 is inserted again in the container neck. To make this possible without closing the switch 40 the lower circumferential corner of the stopper is beveled as shown at 43 in Figure 2.

Having described my invention, what I claim and desire to secure by Letters Patent is:

1. In a closure lock for containers having a neck, a closure including a portion insertible in said neck and formed with an annular groove, arms straddling said closure, said arms register-

ing with and extending into said annular groove preventing removal of said closure from the neck, a spreader element associated with said arms, an electro-magnet positioned to influence said spreader element, and means energizing said electro-magnet from a remote point for actuation of said spreader element to release the closure.

2. In a closure lock for containers having a hollow neck, a closure including a portion insertible in said neck to close the same, said closure portion being formed with an annular groove, a pair of diametrically-disposed arms carried by said neck inwardly thereof, said arms including portions seatable in said groove to lock said closure in said neck, means loading said arms toward said groove, said arms including juxtaposed portions located laterally of said closure, a movable spreader element carried by said neck adjacent said juxtaposed portions, and means for moving said spreader element between said juxtaposed portions, whereby to spread the same and simultaneously disengage both of said arms from said annular groove of said closure.

RALPH C. STALEY.
